(57) **CLAIM**

The ornamental design for a fan and light mount assembly, as shown and described.

DESCRIPTION

FIG. 1 is a front, right perspective view of a fan and light mount assembly.

FIG. 2 is a front view of the fan and light mount assembly of FIG. 1.

FIG. 3 is a rear view of the fan and light mount assembly of FIG. 1.

FIG. 4 is left side view of the fan and light mount assembly of FIG. 1.

FIG. 5 is a right side view of the fan and light mount assembly of FIG. 1.

FIG. 6 is a top view of the fan and light mount assembly of FIG. 1; and,

FIG. 7 is a bottom view of the fan and light mount assembly of FIG. 1.

The features shown in long-and-short broken lines are boundary lines and form no part of the claimed design. All other broken lines (e.g., the even broken lines) correspond to environmental structure and form no part of the claimed design. The lighter solid lines denote surfaces and/or contours.
